Primary Examiner — Jack Reickel*Assistant Examiner* — Salamah Jordan(74) *Attorney, Agent, or Firm* — Dennemeyer & Associates LLC; Victoria Friedman(57) **CLAIM**

The ornamental design for a training device, as shown and described.

DESCRIPTION

FIG. 1 is a front view of the training device;
 FIG. 2 is a back view of the training device of FIG. 1;
 FIG. 3 is right side view of the training device of FIG. 1;
 FIG. 4 is left side view of the training device of FIG. 1;
 FIG. 5 is top view of the training device of FIG. 1;
 FIG. 6 is a bottom view of the training device of FIG. 1;
 FIG. 7 is a front view of the training device of FIG. 1 turned inside out; and
 FIG. 8 is a back view of the training device of FIG. 1 turned inside out.
 The broken lines of FIGS. 7-8 illustrate portions of the training device that form no part of the claimed design.

1 Claim, 6 Drawing Sheets(56)
